LICENSE PLATE ATTACHMENT

Norman W. Roper and William O. Dodd, Jr.,
San Angelo, Tex.

Application July 14, 1952, Serial No. 20,602

Term of patent 14 years

(Cl. D14—6)

To all whom it may concern:

Be it known that we, Norman W. Roper and William O. Dodd, Jr., citizens of the United States, residing at San Angelo, in the county of Tom Green and State of Texas, have invented a new, original, and ornamental Design for a License Plate Attachment, of which the following is a specification, reference being had to the accompanying drawing, forming part thereof.

Figure 1 is an elevational view of a license plate attachment, showing our new design.

Figure 2 is an end view thereof.

The dominant features of our design reside in those portions shown in full lines.

This application is a continuation-in-part application of our application Serial No. D. 18,578, filed on February 4, 1952, now abandoned.

We claim:

The ornamental design for a license plate attachment, as shown and described.

NORMAN W. ROPER.
WILLIAM O. DODD, JR.
